Attorney

UNITED STATES PATENT OFFICE.

JACOB STIRISS, OF NEW YORK, N. Y., ASSIGNOR TO THE LARVEX CORPORATION, OF BROOKLYN, NEW YORK, A CORPORATION OF NEW YORK.

NOZZLE FOR ATOMIZERS.

Application filed July 25, 1924. Serial No. 728,229.

This invention relates to nozzles for atomizers and particularly to nozzles that are used in producing a fine spray from a liquid that will emerge from an outlet in the form of a cloud and the object of the invention is to provide means for keeping the liquid outlet open where solids are in suspension and to give the outgoing liquid a rapid gyratory movement before it is forced out of the vent 10 in the nozzle.

Another object in the invention is to so fit and force the parts together that leather or other packing, which deteriorates, may be dispensed with yet the parts are water tight 15 and readily assembled without the aid of tools and with the minimum of skill and finally certain passages are so located in the nozzle at a point that the liquid will drain therefrom when the device is at rest 20 and where the liquid on evaporation will leave no deposit.

These and other objects and details of the invention are more fully described in the following specification, set forth in the appended claims and illustrated in the accompanying drawings; wherein:

Fig. 1 is a side elevation of an atomizer showing the improved nozzle applied thereto.

Fig. 2 is an enlarged sectional view through the nozzle.

Fig. 3 is a plan and end view of the outlet cap.

Fig. 4 is a plan view of the outlet shell for gyrating the liquid.

Fig. 5 is an interior view of said outlet shell.

Fig. 6 is an exterior face view of the same.

Fig. 7 is a side elevation of the head for the outlet tube.

Fig. 8 is a front view of the same.

Figures 9 and 10 represent sections taken near the periphery of the shell shown in

Figure 5. These views show the manner in which the opening is formed in the end of the shell so as to produce an opening which is closed in a direction parallel to the axis of the shell and is substantially tangential 50 to the interior of the wall of the shell.

In atomizers of the character to be herein-after described and where very minute passages and outlets are employed these pas-

sages and outlets are liable to become obstructed and clogged by solids like powders that are mixed with the liquids or by salts or compositions that are held in suspension and that are liable to remain in the nozzle when the liquid evaporates.

This objectionable feature is overcome to some extent by making the parts detachable so that they may be taken apart and cleaned but in screwing the parts together again washers of leather or other packing have 65 been used to prevent the leakage that the internal pressure produces but such packing must be renewed with each separation of the parts and skill is necessary to complete the re-assembling.

To produce the whirling and gyratory movement of the liquid just before its discharge as a spray it has been passed through spiral channels of very minute dimensions but the present invention employs preferably but one outlet and guiding means to assist the liquid in its gyratory course before leaving the outlet as a spray.

The nozzle is attached to the outer end of a tube 10 having the loop or bend 11 that is 80 for the insertion of the finger of the operator and said tube besides being for the passage of liquid from a bottle that the stopper 12 is designed to fit, is also a piston rod for a piston in the cylinder 13 having an inlet 85 tube 14 that is adapted to extend to the bottom of said bottle.

At the end of the tube is a head 15 whose neck 16 is shrunk on or otherwise secured to the tube, fitting against the flange 17 and 90 having a tapered forward extension 18.

Loosely secured and swivelled on the head 15 by means of the flange 17' is a nut 19 having interior screw threads a short distance back of its forward end and having 95 its outer surface knurled or roughened for manipulation when being rotated on the head but having clearance from the extension 18.

The interior screw threads of the nut 19 are adapted to co-operate with external threads on the outlet cap 20 having a fine orifice 21 and tapered on its interior to fit the tapered extension 18 and be drawn and jammed thereon by the nut 19 to form a 100 practically watertight closure so that no liquid will escape except through the orifice.

21. The close fitting of the cap on the head will render any other packing between these parts unnecessary as the angle of taper of the two parts is identical and the fit is 5 perfect.

5 The assembling and separation of the nut and the cap is brought about by the rotation of the nut only and the cap is held stationary by the operator so that the cap 10 and its contents may be retained in a fixed relation with the tube 10 both while the nut is binding it in place or releasing it.

Within the cap 20 is located a shell 22 having an open inner end and a rearwardly 15 extending stem 23, while at the edge of its face is a circular beading or pathway 24 rising above said face spirally and beginning at an opening 27 from the inside of the shell so that the liquid ejected there- 20 from will travel around the bead and within the cylindrical wall of the shell.

The operation of forming the opening 27 in the sheet metal shell is shown in Figs. 9 and 10 where in the former the beading 24 25 is shown with an abrupt declivity 29 that is adapted to be sheared by a tool and carried down to form a lip or extension 28 to the beginning of the incline of the bead 24 and at the same time provides the opening 27. By this means the water or liquid that is discharged from the shell is absolutely prevented from following an axial direction but can only escape tangentially and up and around the beading 24.

35 As will be seen in Figs. 3 and 4 the upper side of the cap 20 and the flattened surface of the stem 23 are provided with the word "Top" so that when the parts are assembled the outlet 27 of the shell 22 will be positioned at the upper part of the shell, so that, after use, the liquid with its solid 40 contents will drain towards the bottom and leave no residue in the outlet if the liquid should evaporate.

45 The chances of obstruction and clogging are thus relieved by the single, short and wide outlet 27 and orifice 21 with the means of drainage by which residues will not remain about these outlets or which might be 50 blown out by a blast from the pump.

In addition to the advantages afforded by the stem 23, it is also used to separate the shell 22 from the cap 20 as the shell closely fits the tapering interior of the cap and is held tightly therein by pressure of the liquid when the atomizer is in operation.

60 The construction above described permits of the use of sheet metal entirely in the make up of the invention and no castings and finishing of the same is necessary. The parts are reduced to the minimum and readily assembled or separated as described.

65 It will be seen that the nut 19 is not threaded at its inner edge but is left blank so that the cap may be properly located

within the same so that the threads begin to operate to draw the cap inward.

What I claim as new is:

1. In a nozzle for atomizers, the combination of a tapered head at the end of a tube, 70 a correspondingly tapered cap having a discharge orifice and screw-threads, a nut swiveled on the head and adapted to engage the threads of the cap to force it on the head, and an inwardly opening frusto-conical shell 75 disposed within said cap and corresponding in taper therewith, the shell being of larger diameter at its closed end than the outer end of the cap, whereby the shell is forced into water tight engagement with the cap when liquid is forced against the inner side of the shell, and the closed ends of said shell and cap being in spaced relation to provide a whirl chamber, said shell having, in its closed end an opening which is closed in a direction parallel to the axis of the nozzle and shell and is tangential to the wall of said whirl chamber.

2. In a nozzle for atomizers, the combination of a tapered head having a flange and located at the end of a tube, a correspondingly tapered cap having an orifice and screw-threads, a nut swiveled on the flange and adapted to engage the threads of the cap and draw it on the head, an inwardly opening tapered shell corresponding with the taper of the cap and adapted to fit within same so as to leave a whirl chamber between their end walls, said shell having, in its closed end an opening which is closed in a direction parallel to the axis of the nozzle and shell and is tangential to the wall of said whirl chamber, and a circular inclined track leading from said opening toward the open end of the shell and adapted to cooperate with said opening to impart a whirling motion to the liquid discharged through the opening.

3. In a nozzle for atomizers, the combination of a tapered head at the end of a tube and having an annular flange, a correspondingly tapered cap having a discharge orifice and exterior threads, a nut swiveled on the flange and adapted to engage the cap and draw it into water tight relations with the head, an inwardly opening frusto-conical shell adapted to engage the interior of the cap in water tight relation and with the closed ends of the shell and cap spaced from one another to provide a whirl chamber, when liquid pressure is applied within the shell, said shell having an opening which is closed in a direction parallel to the axis of the nozzle and shell and is tangential to the wall of said whirl chamber, and a spiral beading on the outer face of the shell beginning at the said opening and terminating as a shoulder penetrated by said opening and having an interior lip.

4. In a nozzle for atomizers, the combi-

nation of a suitable head through which liquid is adapted to be fed, a circular cap carried by the head and provided with a centrally disposed discharge orifice, a shell positioned within the cap and having a closed end spaced from the closed end of the cap to form a whirl chamber and which closed end of the shell is provided with an interior substantially helical channel terminating in a shoulder which is cut away to provide an opening which is closed in a direction parallel to the axis of the nozzle and shell and is tangential to the wall of said whirl chamber, said helical channel being adapted to cooperate with the tangential opening to impart a whirling motion to liquid discharged through such opening into the whirl chamber between the closed end of the shell and the closed end of the cap. 15

5 In testimony whereof I hereunto affix my 20
signature.

JACOB STIRISS.
